PNEUMATIC PUMP

Alexander R. Harvie, Orillia, Ontario, Canada

Application December 30, 1949, Serial No. 135,893

7 Claims. (Cl. 103—248)

1

This invention relates to improvements in a pneumatic pump for supplying water, from a well, tank or cistern, under pressure as to a faucet.

An object of the invention is to provide an apparatus for lifting liquid under pressure from a source of supply that is automatic and self regulating, requiring the minimum of attention.

A further object of the invention is to provide a pneumatic pump consisting of a chamber, immersed in a water supply, to and from which compressed air is intermittently admitted and bled by a novel float-operated control valve of improved structure and reliable, non-stalling, rapid action.

A further object of the invention is the provision of a compressed air operated pneumatic pump of the nature and for the purpose described that is characterized by structural simplicity having but few working parts; is durable and designed to give long trouble-free service; compact and easy to install; and capable of manufacture and operation at reasonable cost, whereby the same is rendered commercially desirable.

To the accomplishment of these and related objects as shall become apparent as the description proceeds, the invention resides in the construction, combination and arrangement of parts as shall be hereinafter more fully described, illustrated in the accompanying drawing, and pointed out in the claims hereunto appended.

The invention will be best understood and can be more clearly described when reference is had to the drawing forming a part of this disclosure wherein like characters indicate like parts throughout the several views.

In the drawing, the pump chamber in vertical section is shown immersed in a tank of water, the remaining parts of the pump appearing in elevation.

The pump chambered casing 1 is of cylindrical or oval form, with a closed bottom 2, and an open top 3 provided with a removable water-tight cap or cover 4. Installed in a water tank, well or cistern such as shown at 5, it is immersed in the water or other liquid so as to be at all times covered by the liquid.

To a pipe or nipple 6 threaded in a central bore 7 through the bottom 2 a T fitting 8 connects that has a screened inlet pipe 9 on one branch and an outlet supply pipe 10 reaching to a faucet 11 or the like on the other branch. Between the screened intake 9 and the T there is a one-way, holding inlet valve 12 and between the T and the faucet 11 there is another one-way outlet valve 13. If the pressure in the base of the reservoir 5 be greater than in the chamber 1,

2

the inlet valve 12 will open, but if the pressure in the chamber 1 be greater the said valve will remain closed. Similarly, if the pressure in the chamber exceeds the normal atmospheric pressure together with the weight of the column in the supply pipe 10 to the faucet 11, the outlet valve 13 will open when the faucet 11 is turned on and close, as a holding or check valve when the faucet is turned off.

The pump mechanism comprises essentially an air line or inlet pipe 14 in communication with any desired constant supply of air pressure, not shown, preferably entering the chamber 1 through the cover plate 4 and an automatic air bleed tube 15 likewise extending through the cover. Thus in removing the cover, not only is the interior of the chamber accessible but all the pump mechanism, save only the two regular plumbing valves 12 and 13, comes with it for easy adjustment, replacement or repair.

Specifically, the air bleed with its associated float-operated sleeve valve is the heart of the pump. The tube 15 passing through the cover in air-tight connection may be vertically adjusted by means of the nuts 16 threaded on the tube and engaging opposite faces of the cover. The upper or exterior end of the tube reaches above the water level and has an outlet opening therein; the lower or inner end extending well into the chamber is closed at the bottom but has a lateral port 17 spaced some distance thereabove. Mounted concentrically on the tube 15 and normally suspended below the air bleed port 17 is a sleeve valve 18 being movable up the tube to cover and close the said port. A pair of spaced rods 19 extend from opposite sides of said sleeve valve at its lower end carrying a cross-piece 20, at a distance beyond reach of the bottom of the tube 15, from which a long float stem 21 drops. Movable along this stem from its headed bottom to the cross-piece 20 is a float 22. This float-operated sliding sleeve valve has been found very satisfactory. When the chamber 1 is empty or almost so the port 17 will be open and air pressure entering by the line 14 escapes through the port and hollow outlet tube 15. At this time, the pressure in the base of the tank 5 forces water in the inlet 9 and past the valve 12 into the chamber causing the float 22 to rise until it reaches the cross-piece 20 and then pushes the sleeve valve 18 up its tube until it closes the port 17, when air pressure builds up to the predetermined point along the inlet valve 12 and providing a pressure supply of water at the faucet 11. To obviate the possibility of the valve just partially closing the port and allowing enough pressure to escape to produce a balance so that the device

40

45

50

55

would stall, I have found it most desirable to provide the sliding sleeve valve with a spring device such as a snap-action toggle mechanism that restrains the valve just before closing and/or opening and then accelerates its travel across the port in either direction. A suitable valve flipper is shown consisting of a centrally bored valve-influencing member 23 threaded on the tube 15 above the port 11 and vertically adjustable on the tube by a pair of nuts 24 to assure its exact setting. Opposite ends of this saddle like member depend as spaced diagonally opposite spring arms 25 to approximately the level of the lateral port. Links 26, longer than the direct radial distance from the sleeve valve 18 to these arms, are pivotally connected at opposite ends to the bottom of the spring arms 25 and the valve 18 near the top. Thus when the float 22 rises to the top of its stem and is exerting pressure against the valve substructure, the spring tension of the arms 25 temporarily resists the upward thrust of the valve until with the water rising high on the float sufficient force is exerted to spread the arms and snap the valve quickly past the port. Similarly, on the falling of the water level in the chamber, the valve does not open the port until the float is left nearly high and dry and then the valve is likewise snapped quickly by the bleed port.

From the foregoing description taken in connection with the accompanying drawings, it will be manifest that a pneumatic pump is provided that will fulfill all the necessary requirements of such a device, but as many changes could be made in the above description and many apparently widely different embodiments of the invention may be constructed within the scope of the appended claims, without departing from the spirit or scope thereof, it is intended that all matters contained in the said accompanying specification and drawing shall be interpreted as illustrative and not in a limitative or restrictive sense.

Having thus described the invention, what is claimed as new is:

1. A pneumatic pump for immersion in a body of liquid comprising a chambered casing, a pipe in communication therewith and extending from the bottom thereof into the immersing body of liquid and having valved inlet and outlet arms, a pipe-line leading into the top of said casing and in communication with a source of air pressure, a bleed pipe projecting through the top of said casing with part of the length thereof extending into the casing and closed at the bottom but provided with a lateral port and a float operated sleeve-valve mounted on said length of pipe extending into said casing and slidable over said lateral port.

2. The combination with the structure set forth in claim 1 of means mounted on said bleed pipe and connected with said valve for delaying the port closing or opening movements thereof and then acting to effect the same rapidly.

3. The combination with the structure set forth in claim 1 of spring means mounted on said bleed pipe and acting on said sleeve valve causing the same to snap quickly over or clear of said port.

4. The combination with the structure set forth in claim 1 of a spring toggle device mounted on said bleed pipe and connecting with said sleeve valve to impart a fast snapping action to the latter.

5. An apparatus of the character described for raising water, and designed for immersion in

a body of water, comprising a chambered casing, a pipe leading into the bottom thereof having a pair of arms one with a valved inlet within said body of water and the other arm reaching to a service pipe and having a holding check valve therein, a pipe line leading into the top of said casing from a source of air pressure, a bleed pipe projecting through the top of said casing with an opening in the exposed upper end and with a length of pipe extending into the casing, closed at its lower end and provided with a lateral port, a float-operated sleeve valve mounted on said length of pipe extending into said casing and slidable over said lateral port and a flexible-type toggle mounted on said pipe and connecting with said sleeve valve to snap the latter over or clear of said port.

6. An apparatus of the character described for raising water, and designed for immersion in a body of water, comprising a chambered casing, a pipe leading into the bottom thereof having a pair of arms one with a valved inlet within said body of water and the other arm reaching to a service pipe and having a holding check valve therein, a removable top on said casing, a pipe line leading into the top of said casing from a source of air pressure, a bleed pipe projecting through the top of said casing with an opening in the exposed upper end and with a length of pipe extending into the casing, closed at its lower end and provided with a lateral port, a float-operated sleeve valve mounted on said length of pipe extending into said casing and slidable over said lateral port and a spring member vertically adjustable on said pipe and connecting with said sleeve valve to snap the latter over or clear of said port.

7. An apparatus of the character described for raising water, and designed for immersion in a body of water, comprising a chambered casing of cylindrical form and having a removable top, a pipe leading into the bottom of said cylindrical casing having a pair of arms one with a valved inlet within said body of water and the other arm reaching to a service pipe and having a holding check valve therein, a pipe line leading into the top of said casing from a source of air pressure, a bleed pipe projecting through the top of said casing with an opening in the exposed upper end and with a length of pipe extending into the casing, closed at its lower end and provided with a lateral port, a float-operated sleeve valve mounted on said length of pipe extending into said casing and slidable over said lateral port, a U-shaped member vertically adjustable on length of said pipe within said casing whose spaced arms are flexible and lie on diametrically opposite sides of said pipe and links connecting the arms thereof with said sleeve valve.
